UNITED STATES PATENT OFFICE.

SAMUEL C. MOREHOUSE, OF NEW HAVEN, CONNECTICUT.

COMBINATION PONCHO AND GROUND CLOTH.

Application filed October 18, 1923. Serial No. 669,431.

To all whom it may concern:

Be it known that I, SAMUEL C. MOREHOUSE, a citizen of the United States, residing at New Haven, in the county of New Haven and State of Connecticut, have invented new and useful Improvements in Combination Ponchos and Ground Cloths, of which the following is a specification.

This invention relates to a combined poncho and ground-cloth for the use of soldiers, campers or others sleeping or camping out.

The primary object of the invention is to provide a combination article of the character described which may be used as a poncho whenever it is desired to use it as such, and which may be also used as a waterproof ground-cloth to provide a dry sleeping or sitting surface for a soldier or camper during stormy or damp weather at night or in the day.

A further object of the invention is to provide an article of the character described which may be converted into a dunnage or sleeping bag for the use and convenience of a soldier or camper in carrying his dunnage or sleeping outfit, and which, when not used for any of the purposes stated, may be folded and secured in compact form for storage, transportation or other purposes.

With these and other objects in view, the invention consists of the features of construction, combination and arrangement of parts, hereinafter fully described and claimed, reference being had to the accompanying drawings, in which:

Figure 1 is a plan view looking toward the inner side of the outfolded article.

Figure 2 is a similar view showing the ground-cloth portion of the same in folded condition.

Figure 3 is a section taken on the line 3-3 of Figure 1.

Figure 3^a is a detail section showing a hollow rim without the use of an internal air tube.

Figure 4 is a section on the line 4-4 of Figure 1.

Figure 5 is a section on the line 5-5 of Figure 2.

Figure 6 is a view similar to Figure 1, showing a modified form of construction.

Figures 7 and 8 are sections taken on the lines 7-7 and 8-8 of Figure 6.

Figure 9 is a view showing the article converted into a dunnage or similar bag.

Figure 10 is an enlarged detail section on line 10-10 of Figure 9.

Figure 11 is a bottom plan view of the bag shown in Figure 9.

Figure 12 is an enlarged detail section on line 12-12 of Figure 11.

Figure 13 is a view showing the device as employed as a floor for a "pup" tent.

In carrying my invention into practice, I provide an article of the character described comprising a main member 1, constituting the poncho proper, and which is, as usual, of oblong rectangular form and made of a sheet of rubberized fabric or other suitable air and waterproof material. This member 1 may be formed of a single piece of the material or of two strips or pieces, as shown, united along the longitudinal seam line 2. The member or poncho 1 is provided at or near the transverse center thereof with a central horizontal transverse slit or opening 3, through which the wearer passes his head in fitting the poncho upon his person for use. The outer or rear face of the member 1 is provided with the usual poncho collar 4, which may be of the ordinary or any approved form and construction. The poncho, when used as such, is designed to be folded transversely along the dotted line a-a, Figure 1, coinciding with the slit or opening 3, the respective portions 5 and 6 of the poncho, on opposite sides of said line a-a, forming the front and back portions of the garment when applied for use. The opposite marginal longitudinal side edges 7 and 8 of the portion 5 are respectively provided with fastening buttons 9 and button-holes 10 and the transverse marginal edge 11 of said portion 5 is provided with a continuous row of button-holes 12. A strip 13 is secured along its edge to the portion 5 parallel with the edge portion 7 and overlying the same, and said strip 13 is provided with button-holes 13' registering with the buttons 9. The portion 100

100

6 is provided on opposite sides of the longitudinal center of its transverse edge with separate marginal portions 14 and 15 respectively provided with button-holes 16 and buttons 17, the marginal portion 14 extending beyond the line of the marginal portion 15, and said portion 15 as shown, having secured thereto a parallel strip 15' similar to the strip 13 provided with button-holes 16' in alignment with the buttons 17. These fastening buttons and button-holes are provided for securing the body member or poncho 1 in various folded or other conditions in the different uses of the device, as 15 hereinafter fully described. The purposes of strips 13 and 15' will be hereinafter described.

Provided upon the inner side of the back half or portion 6 of the member 1 is a ground cloth section or ground mat made up of a pair of fabric strips 18 and 19 and a rim portion 20, together with the section of the fabric composing the poncho portion 6 lying between and bounded by the strips 25 18 and 19 and the sides of the rim 20. The ground cloth or mat section as thus formed extends transversely of the poncho portion 6 and, when in outspread condition, is of greater length than the width of said poncho portion and extends at each end beyond the side edges thereof. The separate strips 18 and 19 are employed, as shown, in order to reduce the amount of material used and to lighten the weight of the article, but of course there may be substituted for these strips a continuous strip of fabric extending the full length of the space bounded by the rim 20. The strips 18 and 19 are stitched or otherwise secured at their inner marginal edges to the poncho portion 6 along the lines 21 and 22, leaving said strips otherwise free so that said strips, with the portions of the rim 20 carried thereby, forming the projecting free ends of the ground mat 45 section, may be folded inwardly and outwardly, as hereinafter described. The rim 20 may be made, as shown in Figures 1, 3, 3^a and 4, of a strip of fabric marginally secured, as at 23, to the strips 18 and 19 and to the body of the poncho section 6, so as to provide an inflatable rim channel bounding the surrounding space and of which the under-half will be formed by the fabric of the ground-cloth and which will extend a 55 distance of several inches above the same when in inflated condition. A tube 24 is provided whereby the hollow rim may be inflated with air whenever desired and whereby the air may be allowed to exhaust, to adapt said hollow rim to collapse substantially in a flat condition. The head end of the ground-cloth, to wit, that end of which the strip 18 forms a part, is shown as square or having its transverse edge straight and 60 parallel with the adjoining side of the pon-

cho cloth, while the other or foot end of the ground-cloth, of which the strip 19 forms a part, is shown as being of triangular form, in which form it may be made when it is desired to employ the ground-cloth as a mattress or floor covering for a specified type of army tent. The head and foot sections of the ground-cloth are capable, when the rim 20 is deflated, of being folded inwardly over upon the poncho section 6, as 70 fully shown in Figure 2, and suitable fastenings are provided for holding the same in this condition. These fastenings may consist of thongs or straps 24', on the outer faces of the strips 18 and 19, adapted to pass through loops 25 on the intermediate portion of the ground-cloth formed by the poncho section 6, and tied or otherwise secured, to hold the folded portions of the ground-cloth in such condition against displacement. When the device is folded and applied for use as a poncho, as described, the side edges of the folded device may be united, if the wearer so desires in order to better protect his person, by engaging one or more of the buttons 9 at one side edge of the back 6 with registering button-holes 13' in the flap 13 of the similar side edge of the front poncho section 5, and uniting the opposite side edges of the portions 5 and 6 by 80 engaging tie cords or the like with registering openings 10 of said portions.

In Figures 6, 7 and 8, I have shown a modified form of my invention in which I have disclosed a different manner of applying the inflatable rim and in which I have also shown an added pillow feature which may be employed. The rim 20^a in this construction is complete in itself, being formed of a complete strip having its edges overlapped and united by stitching to the cloth of the poncho section, as at 23^a, Figure 8, so that a tubular member formed separate from the poncho cloth but secured thereto is provided capable of being inflated and deflated. The pillow feature herein shown consists of a section of fabric 25' superimposed upon the strip 18 and secured around its margins thereto and to the rim portion so as to provide therewith an air chamber capable of being inflated and deflated to serve as a pneumatic pillow at the head end of the ground-cloth or mattress. This pillow may be inflated by means of an inflating tube separate from the rim, or it may communicate with the rim and be inflated and deflated therewith.

Figure 1 shows the combination article outspread, in which condition it may be employed by a soldier or camper to cover the ground and to provide a dry sleeping or sitting surface for the soldier or camper during stormy or damp weather at night or in the day. When so disposed, the ground-cloth portion may be employed as a mattress.

or the underlayer of a bed on which the soldier may directly incline, or he may recline upon a blanket or other covering or bedding material. When sleeping out upon a damp ground, the soldier or camper will thus be protected by the ground-cloth from contact with the damp ground and, by inflating the rim 20, further protection will be secured against any flowing moisture passing over and wetting the occupant or bed clothing, the inflated rim forming a dam margin sufficiently high under all ordinary conditions to divert the moisture and keep it away from the bed space enclosed thereby. In addition, if the user desires, he may fold the portion 5 underneath or over upon the ground-cloth to give additional protection against dampness, or he may use the portion 5 as a bed covering for warmth or to shed water in the event that he is sleeping out in the open without a tent or other overhead protection. Figure 13 shows the manner in which the device may be used by two soldiers occupying an army "pup" tent, 26 indicating in broken lines the outline of the tent. For this purpose, the combination ponchos and ground-cloths carried by the two soldiers may be disposed in parallel relation to cover the floor of the tent and to provide two sleeping mattresses, whereby the soldiers may be protected from the cold and dampness of the ground. When so used, the inflated rim portions of the mattresses will, in the event of rain, or in the presence of slush upon the ground, ward off the water and thus prevent the same from flowing in, so that the occupants of the tent will keep warm and dry. The described angular form of the foot end of each ground-cloth in this connection adapts such ends of two such assembled ground-cloths or mattresses to fit the V-shaped end of a tent of this character. It is to be understood, however, that this shape may be departed from in the use of the device in connection with other forms of tents and when otherwise desired. In the use of the devices within a tent, the portions 5 of the ponchos may be folded under or over upon the mattress sections, or used as bed coverings, as previously described.

The combination article is designed to be folded in compact form, partially or wholly, to adapt it to be used as an ordinary poncho, or to enable it to be packed in close compass for storage, transportation or other purposes. When the ground-cloth section is folded, as shown in Figure 2, the device may be used as a poncho, the wearer slipping it over his shoulders by inserting his head through the opening in the usual way, the collar 4 giving protection around the throat, while the poncho may be buttoned up about the person of the wearer in an obvious manner. When so worn, the folded ground-

cloth or mattress section will lie inside the poncho section 6 and between the same and the back of the wearer, thus protecting it from the rain while the poncho is being used.

In Figures 9, 10, 11 and 12, I have shown another capability of use of the device, in which it is illustrated as shaped to form a dunnage or sleeping bag. In forming the article into a bag, the mattress or ground-cloth section is folded as illustrated in Figure 2, and then the poncho is longitudinally shaped into a cylinder and its marginal portions 7 and 8 united by tucking or inserting edge portion 8 between the edge portion 7 and strip 13 and passing the buttons 9 through the button-holes 10 and 13' of portions 5 and 13. The marginal edges 14 and 15 are then lapped and connected by infolding or tucking the edge 14 into the space between the edge 15 and strip 15' and passing the buttons 17 through the button-holes 16 and 16' of edge 14 and strip 15' so as to form a closed bottom for the bag, as clearly shown in Figure 11. When so shaped and employed, the mattress section will lie at the bottom of the bag in tubular form, giving ample room for the use of the device as a sleeping bag or dunnage bag, as will be readily understood, and by threading a draw-string through the openings 12 in the edge 11 at the top of the bag the top of the bag will be held closed.

In Figures 3 and 4 and in Figures 7 and 8, I have shown fitted within the rims 20—20^a an inner inflatable air tube 26. This tube may or may not be used, as desired, since the rims 20—20^a may be made inflatable and deflatable and capable of holding air without the use of an auxiliary air-containing tube, such as the tube 26. Figure 3^a shows an inflatable rim 20 minus tube 26 as indicating that the latter may be dispensed with, and the same is true with respect to rim 20^a. In practice, the rim sections may be formed in any suitable manner to allow insertion and removal of the air tubes 26, when such air tubes are used.

From the foregoing description, taken in connection with the drawings, the construction, mode of use and purposes of my invention will be readily understood, and it will be seen that it provides a convenient article for the use of soldiers, campers or other persons, in enabling them to use the device as a poncho during stormy weather or as a ground covering or mattress to provide a dry sleeping or sitting surface at all times, thus enabling protection against cold, rain, snow or damp ground to be obtained. The device obviously will be of great value to soldiers and others camping out in securing comfort and giving protection against dampness and various ills caused thereby.

Having thus fully described my invention, I claim:

1. An article of the character described comprising a substantially oblong rectangular sheet of water-proof material provided with a central transverse neck slit and 5 adapted to be folded along a transverse line coincident with the slit to form the shoulder portions and the front and back portions of a poncho, a ground cloth extending transversely of the inner side of the back section 10 of the poncho between said neck slit and the transverse edge of said poncho portion, said cloth including a hollow inflatable rim and end portions adapted to be extended beyond the longitudinal edges of the sheet and 15 to be folded backwardly upon themselves and over upon said sheet, the longitudinal side edges of the sheet being provided with suitable means whereby similar edges of said poncho portions may be united when 20 the sheet is folded into poncho forming condition.

2. An article of the character described comprising a substantially oblong rectangular sheet having a central transverse neck slit and adapted to be folded upon a transverse line coinciding with said slit to form the shoulder portions and the front and back portions of a poncho, a ground cloth forming a flexible bed section extending 25 transversely of the inner side of the poncho back forming portion of the sheet between the neck slit and the transverse outer edge of said portion, said cloth including a hollow inflatable rim and end portions adapted 30 to be extended beyond the sides of the poncho and to be folded backwardly over upon themselves and upon the sheet body, and means for securing said end portions in folded condition, the longitudinal side edges 35 of the sheet being provided with fastening means and the end edge of the poncho back forming portion of the sheet having divided sections extending one beyond the other, said sections being adapted for lapping engagement and being provided with fastening means for engagement with each other.

3. An article of the character described comprising a substantially oblong rectangular sheet having a central transverse neck slit and foldable along a transverse line coincident with said slit to form the shoulder portions and the front and back portions of a poncho, a ground cloth forming a flexible bed section extending transversely of the inner surface of the poncho back forming portion of the sheet between said transverse slit and the outer transverse edge of said poncho portion, said cloth including strips secured at their inner edges at opposite sides of the sheet and an intervening portion of the sheet body, together with a hollow inflatable rim secured to the sheet body and to said flexible strips, the strips and portions of the inflatable rim secured thereto adapted to be extended beyond the

sides of the sheet and to be folded inwardly upon themselves and upon the intervening portion of the sheet body, means for securing said strips and portions of the hollow rim carried thereby in folded condition, and 70 fastening means along the longitudinal side edges of the sheet, whereby similar side edges of the poncho front and back forming portions of the sheet may be united when said sheet is folded to form a poncho. 75

4. An article of the character described comprising a substantially oblong rectangular sheet having a central transverse slit and adapted to be folded transversely along the line of the slit to form the shoulder portions and front and back portions of a poncho, a ground cloth extending transversely of the inner surface of the poncho back forming portion of the sheet between said neck slit and the end edge of said poncho forming portion of the sheet, said cloth including a hollow inflatable rim and end portions adapted to be extended beyond the side of the sheet and to be folded inwardly over upon themselves and upon the intervening portion of the ground cloth, and means for holding said folding ground cloth portions in folded condition, one longitudinal edge of the sheet being provided with a continuous row of button-holes and the other longitudinal edge of the sheet being provided with a continuous row of buttons and a flap having a continuous rod of button-holes registering therewith, and the said poncho back forming portion of the sheet having its outer edge divided and forming sections extending one beyond the other, the shorter of said sections being provided with a row of buttons and a flap having a coacting row of button-holes, and the longer of said sections being adapted to be inserted edgewise between the first-named section and its flap and being provided with button-holes for coaction with the buttons and button-holes thereof. 90 95 100 105 110

5. An article of the character described comprising a substantially oblong rectangular sheet having a central transverse neck slit and adapted to be folded transversely along the line of said slit to form the shoulder portions and the front and back portions of a poncho, a ground cloth forming a flexible bed section extending transversely of the inner surface of the poncho back forming portion of the sheet between said transverse neck slit and the end edge of said portion of the sheet, said cloth including a hollow inflatable rim and end portions adapted to be extended beyond the sides of the sheet and to be folded inwardly over upon themselves and upon the intervening portion of the ground cloth, the said outer end edge of the poncho forming back portion of the sheet having divided sections, one extending beyond the other, a row of eyelets upon the 115 120 125 130

longer end section, a row of buttons upon the shorter end section, a flap upon said shorter end section provided with a row of eyelets, a row of eyelets extending continuously along one of the longitudinal edges of the sheet, a row of buttons extending continuously beyond the other longitudinal edge of the sheet, a flap overlying the latter-

named longitudinal edge of the sheet and provided with eyelets registering with said buttons, and a continuous row of eyelets extending along the outer edge of the poncho front forming portion of the sheet.

In testimony whereof I affix my signature.

SAMUEL C. MOREHOUSE.
